UNITED STATES PATENT OFFICE

ALEXANDER PATERSON, OF BUFFALO, NEW YORK

MEMBER FOR USE IN THE PRODUCTION OF CONVEX METAL SHEETS AND METHOD FOR
PROCESSING THE SAME

Application filed January 18, 1929. Serial No. 333,420.

This invention relates to the art of rolling sheet metal and proposes an advantageous form of strip metal which is to be used in the production of final gauge sheet metal together with a novel method of processing the same.

It is well known that the ultimate thinness to which a single sheet or strip of metal can be reduced is limited by the various rolling factors and in order to reduce the sheets beyond this limit it is necessary to pile or double the sheets to form a pack and reduce the pack. It is also understood that as a result of the rolling operation the sheets reduced, under proper rolling conditions, will have a natural convex cross section. In order to obtain sheets of flat or rectangular form it is, of course, desirable to reduce the convexity of the metal progressively with the reductions in thickness. It may be pointed out, however, that the sheets or packs which are obtained from one source, differ in natural convexity, from those obtained from another source. Consequently for further rolling, it is necessary to design or adjust the rolls specially for rolling the packs from one source and then to redesign or readjust the rolls for the packs from another source or to adapt each pack specially to fit the rolls.

This latter practice is fully disclosed in my companion application filed October 6, 1927 and serially numbered 224,343, in which I propose to form various packs of sheet metal from various sources with a predetermined or standardized convexity. By so doing all such packs may be reduced on the same set of rolls without requiring any change in the design or adjustment of the rolls except insofar as a pack having a different standard of convexity or a standard pack of different thickness is to be reduced.

The present invention which is directed in a general way to packs having a standardized convexity, has, for its principal object, to provide a strip of sheet metal from which single sheets of standard convexity may be directly obtained whereby the packs built up from such sheets will also be standardized.

A further object is to provide a simple, rapid and effective method of producing the

strip from which the convex sheets are obtained.

The invention consists in forming a strip of sheet metal with depressions which extend across its width at specified intervals along its length. By transversely shearing the strip at the center of each depression, individual sheets of convex cross section are provided having a length determined by the width of the strip, a width determined by the distance between successive depressions and a convexity determined by the magnitude of the depression.

The invention is illustrated in the accompanying drawings, wherein:

Figure 1 is a side elevation of a schematic arrangement for depressing and shearing the strip, the magnitude of the depressions being greatly exaggerated for the sake of clearness.

Figure 2 is a section along line 2-2 of Figure 1.

Figure 3 is a view in elevation showing the use of different means for effecting the depressions.

Figure 4 is a fragmentary view of a strip formed with a groove in each depression to indicate the line along which the strip is to be cut.

In the practice of my invention, a hot or cold strip of metal is utilized, a cold strip being preferred which previously has been processed to the point where it is desirable or necessary to divide it into individual sheets for pack rolling. This strip which is indicated at 1, is thereupon passed through a pair of depressing rolls 2 each of which is similarly formed with raised cam surfaces 3. Obviously as the rolls rotate, the opposed cam surfaces 3 grip the strip with alternately increasing and decreasing forces so as to form it with a series of uniform depressions 4 and crests 5, the strip thereby having an undulating longitudinal section. These depressions actually are so small as to be imperceptible to the eye but for the sake of clearness, they are greatly exaggerated in the drawings.

The rolls 2 utilized will, of course be designed to form the depressions in the strip at determined intervals dependent upon the

width of the convex sheet desired inasmuch as the distance between the centers of successive depressions determines the width of the sheets.

- 5 After the depressions are formed, the strip is transversely sheared through the center of each depression to form the individual sheets. The shearing operation may be performed simultaneously with the forming operation 10 but it is preferably performed by suitable means such as the cutters schematically indicated at 6 in the drawings. While the cutters 6 preferably operate to sever the sheets completely from the strip, they may, if desired, 15 be arranged to shear it partially across its width so as to leave a web of metal connecting adjacent sheets, this operation being fully disclosed in my prior Patent No. 741,708 dated October, 1903.
- 20 In order to facilitate the proper severance of the sheets, the cam surface of one or both rolls is preferably formed with a small rib (not shown) so located as to mark the strip across its width and through the center of 25 each depression as indicated at 7 in Figure 4. It is apparent, of course, that the width of the strip determines the length of the sheet while the width of the sheet is controlled by the distance between depressions that is to 30 say the distance between successive marks 7. It is equally apparent that the formation of depressions in the manner described provides the sheets with a convex cross section and since the depressions and crests are uniform 35 the convexities of the various sheets will also be uniform. The sheets may, therefore, be piled or doubled to form packs which obviously will also be of uniform convexity. As a result the succeeding rolling operations 40 of each pack may be performed on the same set of rolls without requiring a special adaptation of the rolls to each pack as set forth in my said application, Serial No. 222,343.
- 45 It will, of course, be understood that any suitable means may be utilized for the purpose of forming the strip with depressions, the rolls shown in Figure 1 merely being illustrative of one suitable mechanism. Another mechanism for this purpose is shown 50 in Figure 3. This mechanism consists of a pair of opposed hammers or dies 8 having a beveled strip-engaging surface 9. The dies 8 are operated at intervals to engage and form the strip with depressions of suitable magnitude 55 so as to provide the desired convexity. The strip after leaving the dies will, of course, be sheared and processed as described in connection with Figure 1.
- An advantageous feature of this method is 60 that it permits the final rolling operations to be performed at points other than the point of manufacture of the strip itself. Thus the strip may be processed to sheet form of standard convexity and then shipped to 65 other points for the final rolling operations

or the unprocessed strip may be shipped to such points and there processed to sheets of finished gauge. The method also has the advantage of being quickly and easily performed with uniform accuracy and consequently less waste and lower cost. 70

Having fully described my invention, I claim:

1. The method of producing sheet metal packs in preparation for final rolling operations consisting in forming a strip of metal with transverse depressions at intervals along its length, said intervals depending upon the width of the sheets to be produced, transversely shearing said strip through each depression to provide the sheets of convex cross section and manipulating said sheets into pack form of convex cross section for further rolling. 75

2. The method of producing sheet metal packs prior to and in preparation for reduction by further rolling which consists in forming a strip of metal with transverse depressions at intervals along its length to provide sheets of predetermined cross-sectional curvatures and cross-sectional areas and forming a pack from a plurality of said sheets, thereby to provide a pack which will conform as to area and outline to a predetermined standard for which the mill which is to effect the further reduction is given a predetermined adjustment. 85

3. The method of producing sheet metal packs prior to and in preparation for reduction by further rolling which consists in forming a strip of metal with transverse depressions at determined intervals along its length to provide sheets of predetermined cross-sectional curvatures and cross-sectional areas, said intervals depending upon the width of the convex sheets to be produced and forming a pack from a plurality of said sheets, thereby to provide a pack which will conform to a predetermined standard for which the mill which is to effect the further reduction is given a predetermined adjustment. 100

4. The method of producing sheet metal packs prior to and in preparation for reduction by further rolling which consists in forming a strip of metal with transverse depressions at intervals along its length to provide sheets of predetermined cross-sectional curvatures and cross-sectional areas, transversely shearing said strip at said depressions and forming a pack from a plurality of said sheets, thereby to provide a pack which will conform as to area and outline to a predetermined standard for which the mill which is to effect the further reduction is given a predetermined adjustment. 115

5. The method of producing sheet metal packs prior to and in preparation for reduction by further rolling which consists in forming a strip with uniform depressions 120

130

throughout its width and at determined intervals along its length to provide sheets of predetermined cross-sectional curvatures and cross-sectional areas, said intervals depending upon the width of the convex sheets to be produced, transversely shearing said strip at said depressions and forming a pack from a plurality of said sheets, thereby to provide a pack which will conform as to area and outline to a predetermined standard for which the mill which is to effect the further reduction is given a predetermined adjustment.

6. A sheet metal pack composed of at least two sheets, each of said sheets being formed with a predetermined cross-sectional curvature and cross-sectional area, whereby the said pack conforms as to area and outline to a predetermined standard for which the mill which is to effect the reduction is given a predetermined adjustment.

15 In testimony whereof I hereby affix my signature.

ALEXANDER PATERSON.
